(57) **CLAIM**

The ornamental design for a display device with graphical user interface with data analysis layout, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display device with graphical user interface with data analysis layout showing the new design; FIG. 2 is a front view of a display device with graphical user interface with data analysis layout showing the new design, in a second embodiment;

FIG. 3 is a front view of a display device with graphical user interface with data analysis layout showing the new design, in a third embodiment;

FIG. 4 is a front view of a display device with graphical user interface with data analysis layout showing the new design, in a fourth embodiment;

FIG. 5 is a front view of a display device with graphical user interface with data analysis layout showing the new design, in a fifth embodiment;

FIG. 6 is a front view of a display device with graphical user interface with data analysis layout showing the new design, in a sixth embodiment; and,

FIG. 7 is a front view of a display device with graphical user interface with data analysis layout showing the new design, in a seventh embodiment.

The broken line showing of a display device with graphical user interface is included for the purpose of illustrating portions of the article and forms no part of the claimed design.
